CLAIM

We claim the ornamental design for a face plate for beverage dispenser, as shown and described.

DESCRIPTION

FIG. 1 is a top front left side perspective view of the first embodiment of a face plate for beverage dispenser showing our new design;

FIG. 2 is a front elevational view of the first embodiment; FIG. 3 is a right side elevational view of the first embodiment;

FIG. 4 is a rear elevational view of the first embodiment;

FIG. 5 is a top plan view of the first embodiment;

FIG. 6 is a bottom plan view of the first embodiment;

FIG. 7 is a top front left side perspective view of the second embodiment;

FIG. 8 is a front elevational view of the second embodiment; FIG. 9 is a right side elevational view of the second embodiment;

FIG. 10 is a rear elevational view of the second embodiment; FIG. 11 is a top plan view of the second embodiment; and, FIG. 12 is a bottom plan view of the second embodiment.

The broken line showing on FIGS. 1, 2, 5, 7-8 and 10-12 is for illustrative purposes only and forms no part of the claimed design.
